UNITED STATES PATENT OFFICE.

ANDREW J. CAMPBELL, OF WASHINGTON, DISTRICT OF COLUMBIA, ASSIGNEE TO
MERGENTHALER LINOTYPE COMPANY, A CORPORATION OF NEW YORK.

TYPE OR MATRICES.

1,115,170.

Specification of Letters Patent. Patented Oct. 27, 1914.

Application filed July 23, 1913. Serial No. 730,621.

To all whom it may concern:

Be it known that I, ANDREW J. CAMPBELL, a citizen of the United States, residing at Washington, District of Columbia, have invented certain new and useful Improvements in Type or Matrices, of which the following is a specification, reference being had therein to the accompanying drawing.

My invention relates to typographical machines such as Linotype machines of the general organization represented in Letters Patent of the United States to Ottmar Mergenthaler No. 436,532 wherein circulating matrices are released from a magazine in the order in which their characters are to appear in print, and then assembled in line, the composed line transferred to the face of a slotted mold, the mold filled with molten metal to form a slug or Linotype against the matrices which produce the type characters thereon, and the matrices thereafter returned through a distributing mechanism to the magazine from which they started. More particularly the invention relates to a special form of matrix for use therein, the said matrix being provided with a laterally extending member adapted to overlap an adjoining matrix, so that the matrix may be employed in connection with other matrices to produce a composite or built-up matrix for various purposes, such as the production of fractions containing an unusual number of numerals, the production of designs of various kinds, and the production of other figures and forms. The most common use of my improved matrix will be for the production of numerical fractions, and for this purpose the matrices illustrated are shown as having their laterally extending members provided, some with formative numerals and others with blanks, two sets or series of matrices being shown, one set with the character-bearing members in position thereon to form the numerator of the fraction, and the other set having their character-bearing members in position to form the denominator, when the said matrices are used interchangeably and in different combinations in producing a composite matrix. It will be understood however that the laterally extending members may be provided with formative characters of other kinds and forms, and that the members may project from one side or

from both sides of the matrix, and may be variously formed and attached to the matrix, either movably or immovably or formed integrally therewith. Further it will be understood that while I have shown my invention in preferred form by way of example, and as applied to the kind of matrix shown and described in said Mergenthaler patent, or as embodied in the commercial Linotype machine, obviously many changes and variations therein and in its mode of application will suggest themselves to those skilled in the art without departing from the limits of the invention. Thus the invention may be used in connection with other styles of typographical machines, or with typecasters, typesetters and the like, or any machines which handle types or dies instead of matrices. Generally speaking I desire it to be understood that I do not limit myself to the specific forms and embodiments herein described nor to any particular form or construction of the parts, except in so far as such limitations are specified in the claims.

In the accompanying drawings: Figure 1 is an elevation of a series of matrices, or sections provided with laterally extending members, certain of them bearing the numerals 0 to 9, the said members being so located on the respective sections that in the composite or built-up matrix they will produce the denominator of the fraction. Fig. 2 is a similar view showing the laterally extending members located to produce the numerator of the fraction. Fig. 3 is an elevation of a composite or built-up matrix in which sections of the forms illustrated in the preceding figures are employed in combination. Fig. 4 is a perspective view of a number of the different forms of sections separated from each other, and showing how they can be combined to produce a built-up or composite matrix. Fig. 5 is an elevation showing the two kinds of matrix sections in slightly modified form. Fig. 6 is a perspective view of a composite matrix built up of two sections of the form shown in Fig. 5. Fig. 7 is a horizontal transverse sectional elevation on the line 7-7 of Fig. 1 showing how the laterally extending character-bearing member is applied to its matrix section.

Referring to the drawings: The matrix

sections A—A, etc., shown in Fig. 1 are each provided with a laterally extending member a ; and the matrix sections B—B, etc., shown in Fig. 2 are each likewise provided with a laterally extending member b , the said members on one section, when the sections are assembled side by side to produce a composite or built-up matrix as shown in Fig. 3, overlapping the next adjacent section, so that the members on one section are given support by the other sections, and such numerals or figures as may be borne by the member of one section, may be associated with the member of the other section. The sections A—A have the members a extending laterally from both sides of the same, and below the member each section has its edge formed with a recess a' . Likewise the members b project laterally from both sides of the sections B, and above the member each section is provided in its edge with a recess b' , the said members and recesses being so located on the respective sections, that when the latter are assembled side by side to form a composite or built-up matrix, the member a of section A will seat in the recess b' of section B, and the member b of section B will seat in the recess a' of section A. A series or set of sections A are shown in which the laterally extending members are provided with formative numerals from 0 to 9, and in which other members are employed which are blank. The series of sections B includes sections bearing formative numerals from 0 to 9 and other sections having blank members, as a result of which assortment of sections, various forms of fractions containing in their numerators and denominators various arrangements of numbers or numerals may be produced, by employing the different sections, interchangeably in different combinations and relations. For instance in Fig. 3 a built-up or composite matrix is shown to produce a fraction in which the numerator contains two numerals and the denominator three numerals, with the numerator symmetrically or centrally arranged with respect to the denominator. Three sections A are employed in this composite structure, whose lateral members bear numerals 1, 0, 0, respectively forming the denominator, and four sections B are employed the two outer sections having blank members, and the two inner ones having their members provided respectively with the numerals 2, 4, forming the numerator, the lateral members of the sections A overlapping the adjacent sections B and extending into the recess therein and the lateral members of sections B overlapping the adjacent sections A and extending into the recesses in said sections A, with faces of said members extending flush with each other in a common flat plane.

In Fig. 4 a number of sections A and B

are shown partially assembled, there being two sections of each form, one with a blank member and the other with a character-bearing member. From the position occupied by the projecting members on the respective sections, it will be seen that when the sections are placed together side by side, the projecting members on the sections A, will seat in the recesses in the sections B, and the projecting members of sections B will seat in the recesses in the sections A, thus producing a composite matrix with the member on one section overlapping and seated in the adjacent section.

In Fig. 5 the construction of the sections A', B' is substantially the same as that described, the only difference being that in this case the lateral members a' , b' project from one side only of the sections. The sections may be assembled however in substantially the same manner as the other forms described in different relations and combinations, to produce different forms of fractions; or the sections of this form may be used in combination with those sections having the lateral members projecting from opposite sides, which use is indicated in the composite matrix shown in Fig. 3. The two sets or series of sections shown in Figs. 1 and 2 include sections having the lateral members projecting from one side only, these sections which are similar to those shown in Fig. 5, being shown at the ends of the two series of Figs. 1 and 2, and being adapted for use interchangeably with the other section of the series.

In Fig. 6 one combination of the form of sections shown in Fig. 5 is illustrated, the composite matrix to be produced being made up of one section of each of the forms A' and B' to produce the fraction $\frac{1}{4}$. In this matrix the lateral member of one section overlaps and is seated in a recess in the other section.

The lateral members may be applied to the matrix sections in any appropriate and suitable manner. They may be integral with the sections, or they may be formed as a separate member and attached to the sections either movably or immovably. In the form of construction illustrated the lateral members are separate from the sections, and are seated in undercut recesses therein, the adjacent edges of the respective members A', B', being chamfered so that when they meet in the assemblage of the sections side by side, a horizontal formative indentation will be formed which will produce in the casting, a horizontal printing line separating the numerator from the denominator. With the lateral members formed and applied in this manner to the respective sections, they will act in the built-up matrix, by overlapping and seating in the recesses in the adjacent sections, to lock the individual sections together.

ual sections together with sufficient firmness to enable the series of sections to be handled as a unit.

Having thus described my invention what

5 I claim is:

1. A type or matrix section constructed for circulation in a typographical machine and adapted to be set in line therein with other sections and provided with a laterally 10 extending member adapted to overlap and seat against the front face of an adjoining section.

2. The combination of a plurality of type or matrix sections adapted to be set side by side in a composed line, and each provided with a laterally extending member overlapping and seated against the front face of the adjacent section.

3. A composite type or matrix comprising 20 a plurality of sections adapted to be set side by side in a composed line and provided with laterally extending members overlapping and seated against the front faces of adjacent sections.

25 4. A type or matrix section constructed for circulation in a typographical machine and adapted to be set in line therein with other sections and provided with a character bearing member projecting laterally from 30 its front face and adapted to seat in a recess in the front face of an adjoining section.

5. A type or matrix constructed for circulation in a typographical machine and adapted to be set in line therein with other 35 type or matrices and comprising a plurality of sections, one provided with a recess in its front face, and the adjoining one provided with a character bearing member projecting laterally from its front face and seated in 40 said recess.

6. A type or matrix comprising a plurality of sections adapted to be set side by side in a composed line, and each provided with a recess in its front face and with a 45 character bearing member projecting laterally from such face, the laterally extending member of one section being seated in the recess of the adjoining section.

7. A type or matrix section adapted to be 50 set in line with other sections and provided with a character bearing member projecting laterally from its front face and formed with an adjacent recess in such face.

8. The combination of a plurality of type 55 or matrix sections adapted to be set side by

side in a composed line, and each provided with a laterally extending member, the member of one section being offset with relation to the member of an adjoining section and overlapping and seated against the 60 front face of the latter section.

9. The combination of two series of matrix sections provided with laterally extending members bearing complementary portions of a composite character, the members 65 on the sections of one set being adapted to overlap the sections of the other set.

10. The combination of two series of matrix sections provided with laterally extending members bearing complementary portions of a composite character and adapted 70 to be used interchangeably in different combinations, with the members on one section overlapping the adjoining sections.

11. A type or matrix section constructed 75 for circulation in a typographical machine and adapted to be set in line therein with other sections and provided with a character bearing member extending laterally from opposite sides of the same and 80 adapted to overlap and seat against the front face of adjoining matrix sections.

12. A type or matrix section constructed for circulation in a typographical machine and adapted to be set in line therein 85 with other sections and provided with a character bearing member projecting laterally from its front face and adapted to overlap and seat against the front face of an adjoining section.

13. A composite matrix comprising a plurality of sections adapted to be set side by side in a composed line and provided with character bearing members projecting laterally from their front faces, the member of 95 one section overlapping and seating against the front face of an adjacent section.

14. A composite matrix formed for use in a typographical machine, and comprising a plurality of sections formed to overlap each 100 other and bearing complementary portions of a composite character, said portions being offset with respect to each other to permit such overlapping.

In testimony whereof I have affixed my 105 signature in presence of two witnesses.
